(57) **CLAIM**

The ornamental design for a watch, as shown and described.

DESCRIPTION

FIG. 1 is a perspective view of a watch, comprised of a watch case and band, according to our new and ornamental design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged partial perspective view of the watch case of the watch of FIG. 1; and,

FIG. 9 is an enlarged partial front view of the watch case of the watch of FIG. 2.

The dot-dash broken lines surrounding portions of the watch illustrate the boundaries of the enlarged views and form no part of the claimed design.
